COMBINED CONTAINER AND CLOSURE THEREFOR

Donald W. Donovan, Glastonbury, Conn., assignor to
Monsanto Company, St. Louis, Mo., a corporation of
Delaware

Continuation-in-part of design application Ser. No. 8,253,
Aug. 10, 1967. This application May 10, 1968, Ser. No.
11,882

Term of patent 14 years

Int. Cl. D9—04

U.S. Cl. D9—219

FIG. 1

FIG. II

FIG. III

FIG. IV

FIG. V

FIG. VI

FIG. VII

FIG. I is an exploded perspective view of a combined container and closure therefor showing my new design;

FIG. II is an exploded side elevational view thereof;

FIG. III is a side elevational view showing the closure mounted on the container;

FIG. IV is an end elevational view thereof;

FIG. V is a top plan view thereof;

FIG. VI is a sectional view taken along line VI—VI of FIG. V; and

FIG. VII is a sectional view taken along line VII—VII of FIG. V.

This is a continuation-in-part of design application Ser. No. 8,253 filed Aug. 10, 1968 and now abandoned.

I claim:

The ornamental design for a combined container and closure therefor, substantially as shown and described.
